SLIDING DOOR

Anthony Henry Richard, Alexandria, La.

Application July 3, 1934, Serial No. 733,639

7 Claims. (Cl. 189—60)

This invention relates to improvements in sliding doors, and its objects are as follows:—

First, to provide a door composed of a plurality of tubes, each longitudinally slotted in a straight line at one place, said tubes being so interfitted at the slots as to compose an articulated door panel which is readily conformable to the curvature of a track.

Second, to provide an articulated door panel which is perfectly water-proof insofar as the passage of water from one side to the other of the panel is concerned, the individual tubes serving as gutters to conduct any water that might enter them to the sides of the door where it runs down the guide channels.

Third, to provide an articulated door panel, the slotted tubes of which are capable of being instantly interfitted or separated from each other merely by sliding the tubes lengthwise relatively to each other when separate from the guide channels.

Fourth, to provide an articulated door panel of the foregoing description which possesses a sufficient degree of adaptability to guide channels which may possibly be out of line, enabling the tubes to adjust themselves to the twisted condition of the frame and to continue working without any appreciable binding in the opening and closing of the door.

Fifth, to provide a simple locking arrangement for the door, this involving the lowermost tube as the support for the locking rods, said tube being of a special shape to abut the door jamb.

In the drawing:

Figure 1 is an elevation of an enclosure, in the opening of which the improved door is shown in its closed position.

Figure 2 is a section taken substantially on the line 2—2 of Figure 1.

Figure 3 is a detail longitudinal section taken on the line 3—3 of Figure 1, particularly illustrating the finger grips of the locking arrangement.

Figure 4 is a detail section taken on the line 4—4 of Figure 1, particularly showing how one of the locking rods engages an adjacent guide channel.

The improved sliding door is herein intended for use on a truck, but the door is not confined to this use because it is applicable to garages, and other similar enclosures. In Figure 1 the truck body 1, herein known as the enclosure, has an opening 2 which is flanked at the sides by guide channels 3. These are parallel to each

other, and they stand perpendicularly to a jamb 4 which, in the case of the truck, is its floor.

The perpendicularity of the guide channels extends only to the substantial height of the opening 2. There the channels turn on a curve 5 (Fig. 2) and extend inwardly of the enclosure as at 6. According to the present showing the channel extension 6 runs parallel to the top 7 and closely thereto. The extension is not necessarily close to the top, nor is it necessarily at right angles to the upright parts 3 of the guide channels as shown. The upright parts of the guide channels have registering holes 8. The jamb 4 has a fixed detent 9.

Situated in part of the guide channels is the door generally designated 10. The meaning of the statement that the door is situated partly in the guide channels is that it stops short of the length of the channels as at 11 (Fig. 2), and that only the lateral extremities of the door fit in the channels, the door being situated therebetween in a spanning position as clearly shown.

This door is composed mainly of tubes 12. All of the tubes are alike excepting the bottom and top tubes 13 and 14. Each of the tubes is longitudinally slotted in a straight line at one place as at 15.

The tubes are loosely interfitted by sliding the flange parts adjacent to the respective slots in the slots of companion tubes so that two flange parts of an adjacent pair of tubes will occupy the slot of an intermediate tube which thus acts as a connector. The result of this mode of connection is a staggering of the tubes, there being an outside series and an inside series. The slots of the outer series face inwardly toward the enclosure 1, while the slots of the inner series face outwardly. The tubes are staggered in relationship, but the tubes on the inner series act as positive water stops, serving as gutters to drain off any rain water that might enter them to the sides of the door.

The difference in the bottom tube 13 from the remaining tubes is that a portion thereof is made square as at 16. In other words, the bottom tube is half round and half square in cross section, and it has the same cross section from end to end. The front of this tube has a short slot 17 (Fig. 3) which contains and guides the shanks 18 of finger grips 19. These are fixedly carried in any convenient way by locking rods 20 (either round or non-circular in cross section). The rods are appropriately supported and guided in the bottom tube 13, for instance by end pieces 21 of which one is shown in Figure 4. A com-

pression spring 22 at the near ends of the locking rods (Fig. 3) tend to separate the rods and hold them in locking engagement with the registering holes 8.

5. A hasp 23 on the bottom tube 13 is designed to fit upon the detent 9. When the shackle of a lock 24 is inserted through the holes in the detent and hasp the door may be secured in the closed position.

10. The difference in the top tube 14 lies in its having at least one lug 25 to which one end of a spring 26, or equivalent counterbalancing means is attached. The opposite end of the spring is anchored somewhere within the enclosure. The function of the counterbalancing means is to aid the opening and closing movements of the door, whether the door panel be in the erect position shown, or situated otherwise, with respect to the enclosure 1.

20. The operation is readily understood. Having removed the lock 24 the operator must press the finger grips 19 together so as to remove the ends of the locking rods 20 from the respective pair of registering holes 8. There are numbers 25 of these holes, and by moving the door up to a new position the locking rods can be engaged with a new pair by simply releasing the finger grips thereby securing the door.

In moving the door in its guide channels the 30 slotted tubes remain practically in the original position relative to each other. There is a slight relative change, but this is to be expected because of the inherent loose interconnection of the slotted tubes, and does not interfere with the 35 free and correct operation. The inner series of tubes slide on the inner flanges of the guide channels, especially when rounding the curve 5 and traversing the extension 6. The tubes of the outer series merely hang upon the flanges 40 of the inner tubes substantially as shown. Those tubes in the erect part of the door panel simply hang upon each other at the flanges, 45 the points of support alternating between the tubes of the inner and outer series.

45. It has been pointed out that the tubes are interfitted simply by sliding them together. A pair of tubes may be stood on the floor with their slots in the front position, whereupon a third tube is slid down on the adjacent flange portions 50 thereby to make a connection. The door panel is virtually a chain of tubes. There is limited loose play between the tubes of the completed door panel to enable any necessary adaptation of the panel to a guiding framework which is not 55 twisted too far out of shape.

I claim:—

1. A sliding door panel comprising a plurality of narrowly slotted, individual tubes interfitted

by mutual interengagement of the flange portions adjacent to the slots.

2. A sliding door panel comprising a plurality of slotted, individual tubes, the slots of succeeding tubes being oppositely directed and the flange portions of the tubes adjacent to the slots being interfitted to mutually support the tubes in staggered relationship.

3. A sliding door panel comprising an inner and an outer series of slotted tubes, the slots 10 of the inner series facing outwardly with respect to the opening of an enclosure, and the slots of the outer series facing inwardly and containing pairs of flange portions of the tubes of the inner series thereby mutually interconnecting the tubes.

4. A sliding door comprising a plurality of longitudinally slotted tubes including top and bottom tubes, interfitted by mutual interengagement of the flange portions adjacent to the 20 slots, thereby mutually connecting and supporting the tubes in parallel but staggered relationship to produce an articulated door panel, said top and bottom tube respectively having a lug and a square bottom, the bottom tube having a short 25 slot, counterbalancing means including a spring attached at one end to the lug and having its other end attachable to an anchorage, locking means in the bottom tube including at least one 30 rod protruding from one end of the tube and finger grips having shanks in the short slot and being operable to move the rod, and guide means for the sides of the door panel, one of the guide means having at least one hole to receive the 35 end of the locking rod.

5. A plurality of longitudinally slotted, individual tubes having the flange portions adjacent to the slot of one tube fitted in the slots of companion tubes to compose a loosely connected chain of tubes for an articulated door 40 panel.

6. A plurality of slotted tubes, alternating in position as regards the relationship of the slots so that the slots of the tubes come next to each other and the remaining tubular parts of the 45 tubes face outwardly and inwardly with respect to a door opening, the flange portions of the tubes adjacent to the slots being interfiting to produce a loosely connected door panel.

7. A door panel comprising two series of interconnected tubes having their axial centers disposed on substantially parallel lines, the near sides of the tubes being slotted and containing pairs of flange portions of adjacent tubes so that a tube in one series couples two tubes in 55 the second series.

ANTHONY HENRY RICHARD.
